DESIGN FOR A COMBINED BOTTLE AND CUP

Henry Dreyfuss, New York, N. Y., assignor to
The American Thermos Bottle Company, Norwich, Conn., a corporation of Ohio

Application May 26, 1937, Serial No. 69,558

Term of patent 14 years

To all whom it may concern:

Be it known that I, Henry Dreyfuss, a citizen of the United States, being a resident of the Borough of Manhattan, city of New York, and State of New York, have invented a certain new, original, and ornamental Design for a Combined Bottle and Cup, of which the following is a specification, reference being had to the accompanying drawing, which forms a part thereof.

Figure 1 is a perspective view of a combined bottle and cup showing my new design;

I claim:

The ornamental design for a combined bottle and cup as shown.

HENRY DREYFUSS.
